UNITED STATES PATENT OFFICE.

TIMOTHY J. COLLINS, OF TOLEDO, OHIO, ASSIGNOR OF ONE-HALF TO
RANSOM & RANDOLPH, OF SAME PLACE.

DESIGN FOR A BARBER'S CHAIR.

SPECIFICATION forming part of Design No. 20,535, dated March 3, 1891,

Application filed January 19, 1891. Serial No. 378,357. Term of patent 3½ years.

To all whom it may concern:

Be it known that I, TIMOTHY J. COLLINS, of Toledo, county of Lucas, and State of Ohio, have invented a new and original Design in 5 Barbers' Chairs; and I do hereby declare that the following is a full, clear, and exact description of the invention, which will enable others skilled in the art to which it appertains to make and use the same, reference being had to the accompanying drawings, and to the letters of reference marked thereon, which form part of this specification.

The drawing represents an isometric perspective of my newly-designed barber's chair. 15 The leading features of the design consist in a chair 1, having a base-support 2, formed with supporting-legs 3, having a lower portion of each curved in relief and a cross-bar 4 between and connected with the legs of 20 each side above the ornamentation thereof, said cross-bar being ornamented with scroll-work in flat relief. Upon the base-support 2 is arranged a seat 5, formed with a horizontal rectangular frame ornamented with two 25 parallel beads 6, and from the rear of the frame-work extend two curved standards 7,

having outwardly-projecting portions 8, from which point they incline toward the top and are joined by a cross-bar, thereby presenting an ornamental back portion. From the outwardly-projecting portions 8 arms 9 project forwardly with a sufficient curve to join the frame-work at the front, the curve to the arms commencing midway their lengths and from which point they are ornamented with a scroll-work curved in flat relief, the arms at this point being rectangular, thereby allowing of any degree of ornamental elaboration desired. The lower portions of the arms are formed with an acute inverse curve 10 to harmonize 35 with the curve of the legs. 40

What I claim is—

The design for a barber's chair having the shape and ornamentation herein shown and described. 45

In testimony that I claim the foregoing as my own I hereby affix my signature in presence of two witnesses.

TIMOTHY J. COLLINS.
